STORAGE BOX

Richard A. Shaw, Greenville, R. I., assignor to
Stackbin Corporation, a corporation of Rhode
Island

Application February 25, 1952, Serial No. 273,260

4 Claims. (Cl. 222—556)

1

This invention relates to a storage box or bin of the type having an open or hopper front.

Usually a box or bin with an open or hopper front has no means for closing the front and thus requires careful handling if the box or bin is to be moved from one place to another.

One of the objects of this invention is to provide a cover which will protect the merchandise within from dust or dirt and will also prevent the merchandise being spilled out of the box when transporting from one place to another.

Another object of the invention is to provide a cover which is so arranged that it may be held in closed position without danger of the cover swinging to open position accidentally.

Another object of the invention is to provide a cover which will be retained in open position so that the contents may be poured out of the hopper front as desired.

With these and other objects in view, the invention consists of certain novel features of construction as will be more fully described and particularly pointed out in the appended claims.

In the accompanying drawings:

Figure 1 is a perspective view of the box or bin with the cover in closed position;

Figure 2 is a fragmental perspective view of the forward end of the box, showing the cover in open position;

Figure 3 is a section on line 3—3 of the front portion of Figure 1;

Figure 4 is a section on line 4—4 of Figure 3;

Figure 5 is a perspective view of the friction member shown in section in Figure 4; and

Figure 6 is a perspective view of the cover alone with its retaining latch.

In proceeding with this invention, I have provided a cover which is of arcuate shape, and I have so pivoted the cover that as it is swung from closed to open position, it will follow closely the upper edge of the front wall of the open hopper-like front of the box. Also the cover is so arranged that its upper edge will fit snugly against the cross bar extending between the upper forward edges of the sides of the bin so that when the cover is in closed position, its opposite edges will be closed to the opposite edges of the mouth of the box which provides the opening for entrance thereto. I have also provided a friction plate which will hold this cover in open position by locating this plate about the pivot for the cover, while a latch engaging the upper edge of the front wall is carried by the cover so as to engage with this upper edge and hold the cover closed when swung to this position.

2

With reference to the drawings, the bin or box has a bottom wall 10 with a back wall 11 extending upwardly therefrom and opposite side walls 12 and 13 extending upwardly from the bottom wall and forwardly from the back wall 11. The front wall 14 extends upwardly on an incline from the forward edge of the bottom wall 10 and the side walls 12 and 13 have portions 15 and 16 stepped inwardly from the side walls 12 and 13 and then continuing to the front wall 14. These side wall portions are strengthened by doubling back their upper edges as at 17 and the front wall 14 is similarly strengthened by doubling back its upper edge as at 18.

15 The upper edges of the upstanding back and side walls 11, 12, and 13 are formed inwardly and then outwardly parallel to the bottom wall forming a shoulder and then upwardly to provide a retaining lip 20 extending along the upper edges of these upstanding walls 11, 12, and 13 while a bar 21 extends across between the side wall lips and completes the fourth side of a retaining rim for the bottom of a box superimposed upon the box or bin herein described. This bar 20 may be provided with some sort of a label holder at 22 if desired.

20 A cover designated generally 23 and shown in perspective in Figure 6 comprises an arcuate plate 24 with opposite side arms 25 having curved flanges 26 extending over the outer surface of the plate 24 and secured thereto such as by welding. These arms 25 are substantially the sector of one fourth of a circle whose radius defines the curvature of the cover 24, there being provided an opening 27 on the axis of the radius of curvature of the plate 24 with stock 28 surrounding the same so as to provide for mounting the cover on the side wall portions 15 and 16. These side wall portions are each provided with an opening 29 and 30 and a pivot pin or rivet 31 having a rounded head on its outer portion and a struck-up head 32 on its inner portion extends through the arm 25, side wall portion 16 and also the off-set overlapping edge of the separate side 13 so as to pivotally mount the cover on the side wall. A friction plate 32 is positioned between the arm 25 and the portion 16 so as to exert a spring pressure upon these two parts and hold the cover 23 in any position of adjustment, but more particularly in open position, when moved to such position.

25 In order to hold the cover in closed position, I have provided a latch which comprises a resilient strip of steel 33 secured by rivets 34 to the outer surface of the curved plate 24 and extending

along this outer surface thence through opening 41 to provide a bight or latch portion 35 and thence extending outwardly again and through an opening 36 as at 37 to provide a handle portion 38 which is beneath a flange 39 extending radially outwardly from the cover. This flange serves to protect the handle 38 of the latch from being struck from above for release. By this arrangement it will be apparent that the bight of the latch 35 extends over the upper edge of the front wall 14 which will hold the cover in closed position, but for release the handle 38 will be lifted to withdraw the latch portion 35 from the upper edge of the front wall, thus permitting the cover to be swung about its pivotal axis from the position shown in Figs. 1 and 3 to the position shown in Fig. 2.

The pivot location on the side wall portions 15 and 16 is substantially equally distant from the lower edge of the bar 21 and the upper edge of the inclined front wall 14, and the curvature of the plate 24 is substantially the arc struck from the center of this pivot point to the lower edge of the bar or forward edge of the inclined front wall 14. By this arrangement the upper edge 40 of the cover will be located in closed position close to the lower edge of the bar 21 or in open position close to the upper edge of the front wall 14. It will also be readily apparent that when the cover is in open position, the friction plate 32 will hold it in this open position, thus permitting the contents thereof to be poured from the bin without the cover closing.

I claim:

1. A portable storage bin comprising a bottom wall, back wall and side walls extending upwardly therefrom, a front wall joining and upwardly and forwardly inclined from the bottom wall leaving an open mouth above its upper edge for entrance into the bin, a cover with side arms pivoted on the forward portion of the side walls to swing in overlapping relationship with the front wall, said cover having a flange at the lower

edge thereof, a resilient latch adjacent the bottom edge of said cover inwardly of said flange and adapted to engage the upper edge of said front wall, and an operating handle on said latch extending through said flange to a position beneath said flange to be protected thereby.

2. A portable storage bin as set forth in claim 1 wherein said latch comprises a strip of material secured to the outer side of said cover, the portion thereof engaging the upper edge of the front wall projecting through the said cover, the handle portion comprising a continuous extension thereof which is bent outwardly therefrom and then downwardly.

3. A portable storage bin as set forth in claim 1 wherein a split resilient washer is positioned between said arms and side walls to maintain the cover in open position.

4. A portable storage bin as set forth in claim 1 wherein said flange extends radially outwardly to serve as a handle for moving the cover.
